UNITED STATES PATENT OFFICE.

JOHN F. O'CONNOR, OF CHICAGO, ILLINOIS, ASSIGNOR TO WILLIAM H. MINER, OF CHAZY, NEW YORK.

COUPLING-RELEASE MECHANISM.

1,336,797.

Specification of Letters Patent.

Patented Aug. 9, 1921.

Application filed October 4, 1920. Serial No. 414,661.

To all whom it may concern:

Be it known that I, JOHN F. O'CONNOR, a citizen of United States, residing at Chicago, in the county of Cook and State of Illinois, have invented a certain new and useful Improvement in Coupling - Release Mechanisms, of which the following is a full, clear, concise, and exact description, reference being had to the accompanying 10 drawings, forming a part of this specification.

This invention relates to improvements in coupler release mechanisms.

The object of the invention is to provide 15 an exceedingly simple and inexpensive connector adapted to be employed between the usual coupler release lever and usual coupler locking pin.

In the drawing forming a part of this 20 specification, Figure 1 is an elevational view of the end portion of a car showing a coupler, release lever and my improved connector employed therewith. Fig. 2 is an elevational view looking toward the end of 25 the car and illustrating more particularly the improved connector. And Fig. 3 is a detail perspective of the connector detached.

In said drawing, an automatic coupler of 30 standard form is shown at 10, the same having the usual locking pin 11 provided with an eye or opening 12 at the top thereof as customary. The drawbar is slidably mounted between draft sills 13 and supported by a detachable saddle plate 14. A channel end 35 sill is indicated at 15 and the coupler release lever is shown at 16, the same having an operating handle 17 and an arm 18 extended over the coupler at the center of the car, said arm having an eye or opening 19 at the outer end thereof in the usual manner. As will be understood by those skilled 40 in the art, the release lever may be of any desired form and will usually be detachably supported on the end of the car and of course operable from the side of the car. All of the parts above described may be of 45 usual or desired form.

In carrying out my invention, the connector is formed by two elements A and B. 50 The element A is of U formation having a horizontally extending bottom section 20 adapted to be passed through the eye 19 and side arms 21-21.

The other element B is also of substan-

tially U formation having a horizontally 55 extending bottom section 22, adapted to be extended through the eye 12, and having upwardly somewhat diverging side arms 23-23. The side arms 23 are made of such length that the upper ends thereof are normally disposed above the eye of the release lever. The ends of said arms 23 are bent so as to provide inwardly and oppositely extended hooks as indicated at 24 within which are adapted to be received the arms 21 of the 60 element A, as shown most clearly in Fig. 3. The hooks 24 extend horizontally and are normally located above the horizontal section 20 of the member A a distance corresponding to the desired amount of vertical 65 lost motion between the two elements to compensate for the inward and outward movements of the drawbar with respect to the car.

The elements A and B are made preferably of round rod or bar material and of such a diameter that they may have the corners or bends therein passed through the eyes or openings 12 and 19. In assembling 70 the device, the member B is properly threaded through the eye of the locking pin and the member A threaded through the eye of the release lever while the latter is detached from its bearing supports. With the lever detached, it is obvious that the arms of the 75 element A may be properly inserted through the hooks 24 of the element B and, after the release lever is secured in its operative 80 position, the two elements cannot become separated or detached.

The connector herein shown and described 85 can obviously be manufactured at a very small expense, and applied with a minimum of labor without the use of any special tools. The necessary lost motions to compensate 90 for inward and outward movements of the drawbar are also provided for as will be obvious.

I have herein shown and described what I now consider the preferred manner of 100 carrying out the invention but the same is merely illustrative and I contemplate all changes and modifications that come within the scope of the claims appended hereto.

I claim:

1. In a coupler release mechanism having a manually operable member provided with an opening therein and a locking pin pro-

105

vided also with an opening therein; a connector comprising two elements each of generally U form, one element being adapted to be centrally supported in upright position within the opening of said member and the other element being adapted to be centrally supported in an upright position within the opening of the locking pin, one of said elements having the ends of its arms hook-shaped and extended around the arms of the other element.

2. A connector for coupler release mechanisms adapted to be used between a manually operable member having an opening and a locking pin having an opening, said connector comprising two elements, one element having a section thereof adapted to be loosely supported in the opening of said member and an upstanding arm at one side thereof, the other element having a section adapted to be loosely supported in the opening of the locking pin and provided with an upstanding arm at one side thereof, said last named arm having a hook at the upper

end thereof within which is vertically 25 loosely received the arm of said first named element.

3. A connector for coupler release mechanisms adapted to be used between a manually operable release lever having an eye 30 and a locking pin having an eye, said connector comprising two elements, one element being of substantially U shape and adapted to be supported in a vertical position in the eye of the release lever, the other element 35 being also of substantially U shape and adapted to be supported in an upright position in the eye of the locking pin, said last named element having the upper ends of the arms thereof hook-shaped and within which 40 are received the arms of the first named element.

In witness that I claim the foregoing I have hereunto subscribed my name this 18th day of Sept., 1920.

JOHN F. O'CONNOR.

Witness:

CARRIE GAILING.
